Patented May 4, 1915.

UNITED STATES PATENT OFFICE.

MAURICE LACHMAN, OF NEW YORK, N. Y., ASSIGNOR TO LACHMAN MANUFACTURING COMPANY, OF NEW YORK, N. Y., A CORPORATION OF DELAWARE.

SHIPPING-PACKAGE.

1,138,121.

Specification of Letters Patent.

Patented May 4, 1915.

Application filed November 8, 1913. Serial No. 799,847.

To all whom it may concern:

Be it known that I, MAURICE LACHMAN, a citizen of the United States, and a resident of New York, in the county of New York and State of New York, have invented certain new and useful Improvements in Shipping-Packages, of which the following is a specification.

My present invention relates to a novel 10 means or devices for securing the heads to the body of containers, particularly non-metallic ones of a paper or straw-board type in which heretofore considerable difficulty has been met in securing the heads to the 15 paper body in a simple, commercial and, at the same time, rigid, efficient manner.

The invention is particularly adapted for use with containers made of paper or similar material which, owing to the increasing 20 scarcity of wood and therefore its increased cost, are coming into great demand and it is as applied to this use that the invention will be described herein.

The object of the invention is to so simplify 25 the manner of securing the heads to the body of the container that the operation merely becomes a coöperating proposition and practically as simple as the act of nailing in the heads of wooden kegs or barrels and at 30 the same time attain a package which will be strong enough to withstand at least as much shipping and rough handling as wooden ones.

The object of the invention is also to 35 cheapen the cost of containers of this type by simplifying and reducing the number of operations necessary to manufacture the package while at the same time maintaining its efficiency.

40 To these ends the invention consists in the novel device or devices for and in the manner of securing the heads to the container and also in the new and novel construction of container hereinafter more particularly 45 described and then specified in the claims.

In the accompanying drawings, Figure 1 50 is a vertical central section through a container embodying this invention. Fig. 2 is a horizontal cross-section taken on the line 2, 2 of Fig. 1 and looking in the direction of the arrows. Fig. 3 is a cross-section through one corner of the container on an enlarged scale, the head being removed and one end 55 of the stay member being shown in its position immediately after being inserted in the

body of the container. Fig. 4 is a plan view of the part shown in Fig. 3. Fig. 5 is a perspective view of the end of the stay member shown in Fig. 3. Fig. 6 is a perspective view of one of the stay members as made up 60 to be inserted in the container. Fig. 7 is a side elevation of one end of a modified form of stay member.

This invention most particularly lends itself to use with a cylindrical type of container such as a keg or barrel and when applied to this use, the body portion of the container preferably consists of a cylinder 65 of paper or other similar material 1 formed in any desired manner. Preferably the cylinder 1 is formed of a number of layers of paper superimposed on each other, preferably by a winding operation, and united to each other by a suitable adhesive. The layers are adhered to each other under pressure whereby a solid wall of any desired thickness is attained. The specific manner of forming the cylinder or body 1 forms no 70 part of this invention and further description will be dispensed with.

2 indicates bands or hoops of metal at each end of the cylinder 1 and forced down over the outer periphery thereof. Each of said bands is preferably provided with an inwardly disposed lateral flange 3 which when 75 the band 2 is forced down in place seats on the edge of the cylinder 1 and protects the raw edges thereof from fraying or other mutilation.

4 indicates a metallic stay member preferably of wire and disposed longitudinally of the body 1. The stay member 4, of which there may be any number disposed preferably about the inner side of the cylinder 1, terminates at each end in a cross member or 80 head which forms a seat or stop for the inner surface of the container head and also forms the means for holding the container head against outward displacement.

The stay member is formed as shown in 85 Fig. 6 with a cross-head at each end, each cross-head consisting of a loop 5 projecting laterally in one direction from the main part 4 of the member and a straight, flexible end 6 projecting laterally in the opposite direction. The two heads are united together by the longitudinal part 4 which is looped or tied over each head as at 7.

The stay member may be formed by taking a length of wire and bending it the 90

requisite distance from the end as at 8 to form the transverse member 6. The wire is then bent back upon itself for a distance from the bend 8 to form the loop 5 and then 5 lapped or tied over the member 6 as at 7 after which the wire proceeds laterally thereto. The formation is the same at each end and the stay member may be readily and quickly formed in a suitable wire-working 10 machine.

The stay members, of which there may be any number, are placed on the inside of the cylinder 1 so that the free ends of the lateral members 6 pass laterally through 15 holes punched or otherwise formed in the side of the cylinder and in the hoop or band 2. The connecting length 4 of the stay member is brought into side contact with the inner periphery of the cylinder, the loop 20 5 projects radially into the cylinder and the flexible member 6 projects laterally therefrom as shown in Fig. 3. Each head preferably merely consists of a paper disk 9 made up preferably of superimposed layers of paper adhered to each other under pressure. The bottom head is first inserted 25 into the cylinder until it seats against the plurality of loops 5 after which an annular metal rim comprising an inner flange 10 and an outer flange 11 in different planes is placed over the end of the cylinder, the flange 10 engaging the outer surface of the head disk 9 and the flange 11 seating on the edge of the cylinder 1. The 30 flexible end of the member 6 is then turned over the rim of the head by a hammer or other suitable tool whereby the head disk 9 is securely clamped between the loops 5 and the flange 10 of the head rim. After 35 the container has been filled with the goods desired to be shipped, the open end is closed in the same manner as described with regard to the bottom head.

As is well understood, after the container 45 is filled and closed, any blow or shock due to handling or dropping the package tends to burst the head in an outward direction. In a package made up in accordance with this invention an outward force or pressure is exerted on the turned over end 6 of the stay members and this is in turn taken up by the stay rod proper or the part 4 which owing to the tie or lap 7 prevents 50 any distortion or displacement of the loop 5.

By arranging the head engaging loop 5 horizontal as previously described, it provides a bearing surface of appreciable extent for the inner surface of the disk 9 but if desired the loop 5 may be arranged vertical as shown in Fig. 7 in which case the head merely seats against the upper side of the loop, the longitudinal member 4 and the transverse member 6 of the stay member being however in this case also tied to each 55 other at 7 so that any strain on the end

of the member 6 will be taken direct by the main stay member part 4. Thus, the assembling of a container constructed in accordance with this invention is a very simple proposition, the stay members being merely inserted through the holes in the sides of the cylinder by hand and the disk and annular rim also placed by hand and at the same time an effective fastening of the heads to the cylinder is attained without any appreciable strain coming on the cylinder and tending to rupture it. Also a clean-cut, smooth appearance is given to the outside of the package. 70

It will be understood that the details of construction may be varied without departing from the spirit of the invention as expressed in the appended claims. 80

What I claim as my invention is:

1. A container comprising a cylindrical 85 paper body, metallic stay members disposed within said body and extending substantially the length thereof, loops formed near each end of said stay members adjacent the ends of the cylindrical body, said loops extending inwardly in a radial direction, heads for each end of said body, said heads resting upon said loops, and flexible extensions 90 extending from said loops through said cylindrical paper body in a radial direction 95 and being adapted to be bent to engage the rims of the heads to secure the heads to said body.

2. A container comprising in combination a cylindrical paper body, metallic stay members disposed longitudinally thereof, loops integral with the stay members and projecting radially within said body with the plane of the loops substantially at right angles to the axis of said cylindrical body, said 100 stay members being twisted about one member of said loops, one member of said loops extending radially through said cylindrical paper body, heads constructed to rest upon said loops, metallic rings engaging the outer 105 surface of said heads and seated on the ends of said body, and means to engage said rings to hold said heads within said cylindrical container and upon said loops. 110

3. A container comprising a cylindrical 115 paper body, metallic stay members having loops radially projecting within said body, a paper disk at each end of the body seated on said loops and a metal rim seated on the end of the body and bearing on said disk, 120 said stay members terminating in hooks engaging said rims.

4. A container comprising a cylindrical paper body, a metal band at each end of said body, metallic stay members disposed longitudinally within said body, loops integral with said members and projecting radially within said body, a paper disk fitting within said body at each end and seated on said loops, an annular metal rim for each disk 130

seated on the end of the body and engaging the outer surface of the disk and extensions of said loops passing laterally through the wall of said body and said bands and adapted to engage said rims substantially as and for the purpose described.

5. As a new article of manufacture, a stay member for securing heads to containers comprising a wire stay, a loop at each 10 end of said wire stay integral therewith and projecting laterally therefrom and an extension of said loop disposed laterally from said wire in the opposite direction.

6. As a new article of manufacture, a stay 15 member for securing heads to containers comprising a straight length of wire terminating at each end in a cross-head having members projecting laterally in opposite directions therefrom, said wire being lapped 20 over said cross-heads.

7. As an article of manufacture, a cylind-

rical paper body to comprise the body of a container, metallic stay members extending longitudinally of said body and substantially the length thereof, loops formed 25 near each end of said stay members adjacent the ends of the cylindrical body, said loops extending inwardly in a radial direction to constitute supports for heads to close 30 the ends of said body, flexible extensions extending from said loops through said cylindrical paper body in a radial direction and being adapted to be bent to be operative to secure heads within said body.

Signed at New York in the county of New 35 York and State of New York, this 7th day of November A. D. 1913.

MAURICE LACHMAN.
